UNITED STATES PATENT OFFICE.

PAUL H. WHITE, OF INDIANAPOLIS, INDIANA, ASSIGNOR TO THE WHITE STEAM WAGON COMPANY, OF INDIANAPOLIS, INDIANA, A CORPORATION OF INDIANA.

STEERING-GEAR.

SPECIFICATION forming part of Letters Patent No. 690,802, dated January 7, 1902.

Application filed May 27, 1901. Serial No. 62,037. (No model.)

To all whom it may concern:

Be it known that I, PAUL H. WHITE, a citizen of the United States, residing at Indianapolis, in the county of Marion and State of 5 Indiana, have invented a new and useful Steering-Gear, of which the following is a specification.

My invention relates to an improvement in the steering-gear of that class of vehicles having the "Ackerman" steering system, in which the steering-wheels are independently supported upon vertical axes on the axle.

The object of my invention is to provide means for shifting the steering-wheels to any 15 desired position and rigidly holding them at any point by means which will transmit the thrust of the wheels directly to the axle and of such character as to allow adjustment thereof by means carried by the vehicle-body, 20 the arrangement being such that the connection with the steering-gear will not be disturbed by the relative movement between the axle and body.

The accompanying drawings illustrate my 25 invention.

Figure 1 is a plan. Fig. 2 is a side elevation. Fig. 3 is a section on line 3-3 of Fig. 1. Fig. 4 is a sectional detail.

In the drawings, 5 indicates the axle, provided at each end with a yoke 6, in which is pivotally supported upon a vertical axis the usual stub-axle 7, adapted to receive a wheel. Each stub-axle 7 is provided in the usual manner with an operating-arm 8, and the ends of 35 said arms are connected together by a link 9. Pivoted upon a vertical axis to one of the arms 8 is a nut 10, adapted to receive the threaded end 11 of a shaft 12, to which is secured a sprocket or gear 13. The opposite end of shaft 40 12 is rotatably mounted in a block 14, provided with vertical spindles 14', which spindles are revolvably supported in ears 15 and 15', formed integral with or secured to the axle 5. Shaft 12 is provided with a pair of collars 16 and 16, 45 which lie upon opposite sides of block 14 and transmit the thrust thereto. In order that the thrust of shaft 12 may be transmitted in a direct line to the axle, said axle has its middle portion substantially in the same plane 50 as the shaft 12, and for convenience in manu-

facture the ear 15 is formed integral with the axle, while the ear 15' is bolted thereto.

It will be readily noticed that, if desired, the nut 10 may be pivoted upon a vertical axis upon the axle and the shaft 12 connected to one of the arms 8 by means of the block 14 and spindles 14', said construction being a mere reversal of the construction illustrated and being its full equivalent. Such an arrangement, however, would be subject to the 55 objection that the sprocket would have a considerable horizontal movement due to the axial movement of the shaft.

In operation the stub-axles 7 may be swung simultaneously about their vertical axes by 60 rotating shaft 12 in one direction or the other, the rotation of said rod shifting nut 10 thereon, and thus swinging the arms 8. The rotation of shaft 12 may be accomplished by means of a chain 17 passing over suitable 65 idlers 18 and 19 to an operating-wheel 20, carried by the vehicle-body, (not shown,) or any other suitable means may be employed.

I claim as my invention—

1. In a steering-gear, the combination with 70 the axle, of a stub-axle pivoted thereto, a threaded shaft, and a threaded nut coacting therewith, one pivotally connected to the stub-axle and the other pivotally connected to the axle, and means for causing a relative rotation 75 between the nut and shaft.

2. In a steering-gear, the combination with the axle, of a pair of stub-axes independently pivoted thereon, a link connecting the two stub-axes, a threaded shaft, and a threaded 80 nut coacting therewith, one pivotally connected to one of the stub-axes and the other pivotally connected to the axle, and means for causing a relative rotation between the nut and shaft.

3. In a steering-gear, the combination with the axle, of a stub-axle pivoted thereon, an operating-arm carried by the stub-axle, a threaded nut pivoted to said operating-arm, on an axis parallel to the pivotal axis of the 90 stub-axle, a rotatable threaded shaft coacting with the nut and pivotally connected to the axle upon an axis parallel to the pivotal axis of the stub-axle, and means for rotating 95 said shaft.

4. In a steering-gear, the combination with the axle, of a pair of stub-axes independently pivoted thereon, an operating-arm carried by each of said stub-axes, a link connecting said 5 stub-axes, a threaded nut pivoted upon one of said operating-arms upon an axis parallel to the axes of said stub-axes, a threaded shaft coacting with said nut and pivotally connected to the axle upon an axis parallel to 10 the axes of the stub-axes, and means for rotating said shaft.

5. In a steering-gear, the combination with the axle, of a stub-axe pivoted thereon, an operating-arm carried by said stub-axe, a 15 bearing-block pivoted upon the axle upon an axis parallel to the axis of the stub-axe, a threaded nut pivoted upon said operating-arm upon an axis parallel to the axis of the stub-axe, a threaded shaft revolubly mount-

ed in the bearing-block and coacting with the 20 nut, and means for rotating said shaft.

6. In a steering-gear, the combination with the axle, of a pair of stub-axes independently pivoted thereon, a link connecting the two stub-axes, an operating-arm carried by each 25 of said stub-axes, a bearing-block pivoted upon the axle upon an axis parallel to the axes of the stub-axes, a threaded nut pivoted upon one of said operating-arms upon an axis parallel to the axes of the stub-axes, a 30 threaded shaft revolubly mounted in the bearing-block and coacting with the nut, and means for rotating said shaft.

PAUL H. WHITE.
